UNITED STATES PATENT OFFICE.

ELIJAH C. BARTON, OF EAST HAMPTON, CONNECTICUT.

GONG-BELL.

SPECIFICATION forming part of Letters Patent No. 345,101, dated July 6, 1886.

Application filed May 24, 1886. Serial No. 203,057. (No model.)

To all whom it may concern:

Be it known that I, ELIJAH C. BARTON, of 5
East Hampton, in the county of Middlesex
and State of Connecticut, have invented cer-
tain new and useful Improvements in Gong-
Bells, of which the following is a full, clear,
and exact description, whereby any one skilled
in the art can make and use the same.

My improvement relates, particularly, to
10 the class of gong-bells known as "single-
stroke;" and my object is to provide such a
bell of simple, compact, and efficient construc-
tion.

Referring to the drawings, Figure 1 is a plan
15 view of my improved bell with part of the
gong broken away to uncover the base-plate.
Fig. 2 is a similar plan view of the bell, but
showing the slide drawn out and about to
trip the hammer to cause it to strike. Fig. 3
20 is a side view of the base-plate and parts at-
tached, gong in central section.

In the accompanying drawings, the letter A
denotes the cast-metal base-plate of the bell;
B, the gong, that is attached to the post c in
25 any ordinary manner, as by screwing it onto
the top of the post, with the edge of the gong
in position to receive the stroke of the ham-
mer.

The base-plate A supports the bell-post,
30 about which is coiled the spring d, with its
ends projecting toward opposite sides of the
plate, the one end being pivoted to the con-
necting-rod e, that joins it to the shorter arm
35 of the hammer-lever f, while the other end of
the spring is pivotally connected to the slide g
by means of the link or rod e'.

The slide g is a flat piece of metal with a
lengthwise slot, g', through which a screw
40 passes to attach it to the base-plate, the head
of the screw g² overhanging the sides of the
slot, so as to prevent the slide from lifting off
from the plate, and causing it to move in a
plane practically parallel to the base-plate,
45 the screw g² serving also, by contact with the
ends of the slot, to limit the endwise movement
of the slide.

The link or rod e' is connected to the slide
g at a point offset from the slot or the line of
it, in order to cause the pull of the spring,
50 through the medium of the rod e', to throw

the slide sidewise as well as lengthwise. The
slide bears a projecting catch, h, with its face
inclined at an angle with the slot g', and its
edge adapted to engage the short arm of the
hammer-lever, the back side of this end f' 55
being rounded or inclined.

The hammer-lever f is pivoted to the base-
plate, so as to swing in the plane of the plate,
with the shorter arm of the lever extending
over the slide and in the path of the catch
as the slide is pulled outward, as shown in
60 Fig. 2 of the drawings. In Fig. 1 the parts
are shown in full lines in their normal pos-
ition, held so under the tension of the spring,
while in Fig. 2 the slide is shown as pulled
outward until the edge of the catch is on the
point of slipping off the end f' of the ham-
mer-lever, and after the catch and hammer-
lever are disengaged the hammer recoils un-
der the pull of the spring and strikes sharply
70 against the gong. The slide, on being re-
lieved from the outward pull, is pulled in-
ward by the same spring, and swings aside on
the screw g² as a pivot by the contact of the
sloping surface of the catch and the rounded
75 end of the hammer-lever (see this position of
the slide in dotted outline in Fig. 1) until the
edge of the catch is reached, when the
slide is swung sidewise by the pull of the
spring, and the catch and hammer-lever re-
engaged and in position for causing another
80 blow of the hammer when the slide is pulled
out. In order to prevent the strain from
breaking off the screw g², the stop a is cast
upon the base-plate in position to be struck
85 by the side projection on the slide just before
the end of the slot would strike the screw
but for this limitation of the play of the slide.

The principal advantage of the within-de-
scribed combination of elements in the strik-
ing mechanism of the bell is due to the piv-
otal connection of the slide and the hammer-
lever with the spring by means of the links or
connecting-rods.

I am aware that it is not new to use a sin-
gle spring in bells of this class, and utilize
both ends to operate the hammer and the slide,
and also that slides with both endwise and
sidewise play are not new, and such devices I
do not broadly claim.

I claim as my improvement—

In combination with a base-plate, A, and attached bell B, a spring with its opposite ends pivotally connected by rods or links to the hammer-lever f and slide g, respectively, the hammer-lever f, the slide g, having lengthwise slot g', catch h, and pivotal connection

to rod e' at a point on the slide offset from the slot, and the screw g'', all substantially as described.

ELIJAH C. BARTON.
